UNITED STATES PATENT OFFICE.

WILLIAM T. LONG, OF AUBURN, WASHINGTON, ASSIGNOR TO C. H. HALSEY, OF AUBURN, WASHINGTON.

WRENCH.

1,109,000.

Specification of Letters Patent.

Patented Sept. 1, 1914.

Application filed February 12, 1914. Serial No. 818,335.

To all whom it may concern:

Be it known that I, WILLIAM T. LONG, citizen of the United States, residing at Auburn, in the county of King and State 5 of Washington, have invented certain new and useful Improvements in Wrenches, of which the following is a specification.

This invention relates to wrenches and has for one object the provision of a simple, 10 strong and durable wrench in which the jaws may be made to approach or recede from each other by an oscillatory movement of the handle and in which the receding movement of the jaws may be arrested at 15 any desired point.

A further object of the invention is to provide a wrench in which the jaws may be disposed in angular relation to the jaw support and locked in such angular relation. 20

20. A further object of the invention is to provide a wrench of such construction that the parts will be protected against injury and may be easily manipulated to effect the desired adjustment.

25. The several stated objects and such other incidental objects as will appear from the following description are attained in a device of the character illustrated in the accompanying drawings, and the invention 30 consists in certain novel features which will be pointed out in the claims following the detailed description.

In the accompanying drawing;—Figure 1 is an elevation of a wrench embodying my 35 present invention. Fig. 2 is a sectional view of the jaws and the parts coöperating therewith. Fig. 3 is a detail perspective view of the swiveled stem and the jaw rigid therewith. Fig. 4 is a detail view of the latch 40 employed to hold the swiveled stem in the position in which it may be set. Fig. 5 is a detail perspective view of the housing or standard in which said latch is mounted. Fig. 6 is a detail perspective view of the 45 thumb latch provided upon the handle. Figs. 7 and 8, respectively, are a perspective view of a pipe-engaging jaw which may be used in connection with one of the nut-engaging jaws of my wrench.

50. Corresponding and like parts are referred to in the following description and indicated in all the views of the accompanying drawing by the same reference characters.

In carrying out my present invention, I 55 employ a handle 1, which may be of any

preferred construction and has one end formed into a segmental gear or rack 2. This end of the handle is fitted between cheek-plates 3 and is held to the said cheek-plates by a pivot-pin or bolt 4 inserted 60 through the parts, as will be readily understood. Adjacent the pivot-pin or bolt the handle is provided with a transverse opening in which is housed a coiled spring 5, the ends of which are adapted to press against 65 the inner faces of the cheek-plates and thereby compensate for wear of the parts and prevent the handle moving laterally after long continued use. The cheek-plates 3 are extended beyond the end of the handle and 70 elongated laterally with respect thereto so as to receive a base-bar 6 having one edge formed with teeth 7 adapted to be engaged by the segmental gear 2. The elongated portion of the cheek-plates constitutes a housing indicated at 8 to fit around the said base-bar and thereby guide the same in the relative movement of the housing and the base-bar in the operation of the wrench. The 75 cheek-plates are connected at their outer edges by a web 9 and are also connected at opposite sides of the handle with small webs 10 whereby a tubular support for the base-bar is provided. Upon the web 9 is provided a sleeve or eye 11 which is adapted to 80 fit around the stem or shank 12, as clearly shown. The said stem or shank 12 has a jaw 13 rigid with one end and preferably formed integral therewith, the said end of the shank or stem being notched as indicated at 14 85 whereby to provide an outer lug 15 through which a fastening bolt or pin 16 is inserted, as shown in Fig. 2.

It will be noted that the notch 14 receives a lug or ear 17 formed upon the base-bar 6 90 and the fastening pin or screw 16 passes through the said lug or ear into the shank or stem so as to form a swivel connection between the base-bar and the shank. The working face of the jaw 13 is preferably disposed at a right angle to the shank and an inclined or beveled lug or tooth 18 is formed at the junction of said face with the shank so that the jaw may more readily engage a hexagonal nut. It will also be noted that 100 the body of the jaw is elongated or provided with a curved web or lip 19 extending from the outer end of the jaw to the lug or eye 15 so that the jaw will have a substantial body and, consequently, possess great 105

strength. The inner portion of the jaw is cut-away or beveled, as indicated at 20 so as to accommodate the correspondingly outwardly inclined portion 21 of the coacting jaw 22. This jaw 22 is constructed with a web or lip 23 corresponding to the web or lip 19 so as to impart great strength to the structure and the inclined or beveled surface 21 constitutes the terminal of a shank-engaging portion or sleeve 24 which is formed with the said jaw and adapted to fit around the shank or stem 12, as clearly shown. The inner opposed faces of this sleeve or shank-engaging portion are flattened so as to engage the flattened sides 25 of the shank in order that while the jaw may move longitudinally upon the shank it cannot rotate about the same. The inclined or beveled face 21 coacts with the working face of the jaw so as to enable the jaw to readily engage a hexagonal nut in the same manner that the lug or projection 18 coacts with the working face of the jaw 13.

The jaw 22 is provided with a notch or recess 26 which receives the eye or ring 11 extending from the housing 8 so that the movement of the housing relative to the base-bar or jaw support will effect a corresponding movement of the jaw 22 upon the shank or stem 12 relative to the jaw 13. The jaw 22 is further provided with a small recess or seat 27 adapted to receive the lug or projection 18 when the jaws are brought together so that they may be made to engage a very small nut or bolt head.

It will be readily understood from the foregoing description, that when the handle 1 is oscillated upon its pivotal connection with the cheek-plates the gear 2 will tend to ride upon the rack teeth 7 and, consequently, relative movement of the handle and the base-bar will be effected. The cheek-plates will, of course, follow the movement of the handle and, consequently, the jaw 22 will be caused to move toward or from the jaw 13, inasmuch as the guide or eye 11 extending from the housing 8 which forms an elongation of the cheek-plates fits within the notch in the jaw 22 and forces the said jaw to follow the movement of said housing and cheek-plates. The bore of the guide or eye 11 is circular so that the stem or shank 12 may rotate easily therein under proper manipulation of the wrench. The end of the shank 12 remote from the jaw 13 is provided with an annular groove 28 through which may pass a pin 29 inserted transversely through the standard or housing 30 which is secured to the adjacent end of the base or rack-bar 6, as clearly shown. This pin 29 by engaging the groove 28 forms a swiveled connection for the adjacent end of the shank so that both ends of the said shank will be supported upon the base-bar in such a man-

ner that the shank may rotate about its own longitudinal axis but cannot move axially along the base-bar or support. The shank may be thus turned into angular relation with the base-bar or support so that the jaws may be caused to engage a nut in a restricted space or in a corner and the wrench manipulated without discomfort or excessive fatigue to the workman. The extremity of the shank beyond the groove 28 is provided with radial slots or notches 31 which are adapted to be engaged by a latch 32 so as to lock the shank in any position in which it may be set. This latch 32 is pivoted within the housing or standard 30 and is provided on its opposite sides with milled thumb-pieces or handle members 33 adapted to extend through and seat in notches 34 formed in the outer edges of the standard or housing 30, as clearly shown. A spring 35 is seated in the end of the base-bar or support and extends between the sides of the standard 30 to bear upon the end of the latch 32 so that the latch will be held normally toward the shank. The latch is provided with a tooth 36 which lies adjacent the spring 35 and thereby prevents the spring slipping from the housing or standard and holds the spring in operative engagement with the latch at all times.

As shown in Fig. 5 the standard or housing 30 is constructed with an open-ended slot 37 to receive the working end of the latch 32 and prevent lateral movement thereof so that the latch will always be in proper position to engage one of the notches 31. The standard is also provided with a circular opening 38 to receive the end of the shank 12 and further provided with an angular opening or socket 39 to receive the end of the base-bar or jaw support. When the latch is in engagement with the stem or shank the finger-pieces 33 will lie flush within the notches or seats 34 so that they will present no projections or obstacles which might interfere with the successful operation of the tool. When it is desired to move the jaws into an angular position relative to the base-bar or jaw-support the latch 32 is released from the end of the shank and the said shank is then rotated about its connections with the support until it reaches the desired angle, after which, the latch is permitted to spring into engagement with the notches or slots 31 in the end of the shank. It will, of course, be readily understood that the jaws may be moved to either side of the support or may be arranged in the longitudinal plane of the handle and will be held in either of said positions by the engagement of the latch 32 with the notches in the end of the shank.

In the ordinary use of the wrench the jaw 13 will be placed in engagement with the nut or bolt-head to be turned and the

handle then swung toward said jaw. This action causes the jaw 22 to move toward the jaw 13 and, consequently, effects a binding engagement of the same upon the nut so that 5 the continued movement of the handle will turn the nut. Upon movement of the handle in the reverse direction the jaw 22 will move away from the nut so as to permit a fresh grip to be had thereon. If it be desired or 10 necessary to effect reverse movement of the nut or bolt without releasing the wrench from the nut, the thumb-latch 40 provided in my present tool will be found highly efficient. Ordinarily, oscillation of the handle 15 to effect such reverse movement of the nut would simply move the jaw 22 away from the jaw 13, but by providing the thumb-latch 40 I am enabled to hold the jaw 22 at any point along the shank and the base-bar. 20 It will be noticed that this thumb-latch 40 is provided with a shank piece or handle member 41 which lies adjacent one edge of the handle and from which extends spaced plates or jaws 42 which fit over the handle 25 and upon the opposite sides of the same. A pivot pin 43 is inserted through these jaws 42 and the handle, and the jaws are provided with gripping faces 44 adapted to engage the adjacent edges 45 of the cheek-plates so 30 that the movement of the cheek-plates will be arrested. Small teeth, indicated at 46, may be provided upon these engaging faces 44 and the edges 45 of the cheek-plates, but these teeth are not absolutely necessary, al- 35 though the provision of the same permits a more positive holding of the cheek-plates. The latch is normally held out of engagement with the cheek-plates by a spring 47 secured to the under side of the thumb-piece 40 or handle member 41 and bearing upon the handle 1 of the tool.

From the foregoing description, taken in connection with the accompanying drawings, it will be seen that I have provided an exceedingly simple and efficient tool which may be readily manipulated in restricted places and without any discomfort to the operator.

In order that the range of usefulness of 50 the tool may be given the greatest possible scope I provide a supplemental jaw 48 which may be fitted to one of the jaws 13 or 22 and thereby convert the tool into a pipe wrench. This supplemental jaw 48 is provided with a serrated working face 49, as 55 clearly shown, and has spaced wings 50 adapted to fit against the opposite sides of the jaw 13 or the jaw 22 and be secured thereto by a pin inserted through openings 60 provided for that purpose. The supplemental jaw is constructed with a notch 51 to permit it to fit close to the shank 12 and also is provided with a tooth or lug 52 on its rear side adapted to engage the recess 27 in 65 the jaw 22 so as to be firmly seated against

the jaw and held against lateral movement thereon without putting excessive strain upon the pin by which it is held in place.

Having thus described the invention what is claimed as new is:—

1. A tool comprising a handle, a jaw support, jaws swiveled thereon, the handle being arranged to oscillate in the longitudinal plane of the jaw support, means whereby movement of the handle will cause one of 75 the jaws to approach or recede from the other jaw, and means to hold said jaw at various points of its receding travel.

2. A tool comprising a handle, a jaw support carried by the handle, the handle being arranged to oscillate in the longitudinal plane of the jaw support, jaws swiveled on said support, and means on the support for locking the jaws in a set position.

3. A tool comprising a handle, a jaw support, a housing inclosing the support and the end of the handle, jaws swiveled upon the support, a connection between one of said jaws and the housing, and a latch mounted upon the handle and adapted to 90 engage said housing.

4. The combination of a jaw support, jaws swiveled thereon, means for effecting relative movement of the jaws, and means carried by the jaw support and acting upon 95 one end of the swiveled mounting of the jaws to hold the jaws in a set relation to the jaw support.

5. The combination of a base-bar having a lug at one end, a standard at the opposite 100 end of said bar, a wrench jaw having a stem swiveled in the said lug and in the said standard, a jaw slidably mounted on said stem, means for moving said slideable jaw to and from the first mentioned jaw, 105 and a latch mounted in the said standard and engaging the end of the stem to lock the same in set relation to the base-bar.

6. The combination of a jaw-support, a housing secured to one end of said support, 110 a wrench jaw having a stem swiveled at one end to the jaw-support and having its opposite end fitted in the said housing, a swiveled connection between said end and said housing, and a latch mounted in said housing and adapted to engage said end of the stem beyond said swiveled connection.

7. The combination of a jaw-support, a housing secured to one end of said support, a wrench-jaw having a stem swiveled at one 120 end to the end of the jaw support and having its other end swiveled within the said housing and provided with radial notches in its extremity, a latch pivoted within the housing and adapted to engage said notches, 125 and means for holding said latch in said engagement.

8. The combination of a jaw support, a housing secured to one end of said support and provided with notches in its opposite 130

sides, and a slot in one end, a wrench-jaw having a stem swiveled at one end to the jaw support and at its other end within the said housing, a latch pivoted within the said housing and adapted to engage the said end of said stem, said latch having one end playing in the slot in the housing and provided on its opposite sides with handle members seating in the notches in the housing, and provided with a retaining tooth at its opposite

site end, and a spring within the said housing bearing against the jaw support and against the latch adjacent said retaining tooth.

In testimony whereof I affix my signature in presence of two witnesses.

WILLIAM T. LONG.
